UNITED STATES PATENT OFFICE.

HEINRICH WILD, OF JENA, GERMANY, ASSIGNOR TO THE FIRM OF CARL ZEISS, OF JENA, GERMANY.

TELEMETER.

939,366.

Specification of Letters Patent.

Patented Nov. 9, 1909.

Application filed June 2, 1908. Serial No. 436,314.

To all whom it may concern:

Be it known that I, HEINRICH WILD, a citizen of the German Empire, and residing at Carl-Zeiss strasse, Jena, in the Grand 5 Duchy of Saxe-Weimar, Germany, have invented a new and useful Telemeter, of which the following is a specification.

The invention consists in an improvement in telemeters, in which a middle casing containing an ocular prism system and two lateral casings each containing an objective system, that is to say, an objective lens and an objective prism, are connected together. The ocular prism system is situated before 15 or includes the two image fields and may either be arranged in front of two separate oculars, which constitute the ocular system in stereoscopic telemeters, or in front of a common ocular, which constitutes the ocular system in coincidence telemeters. Telemeters of the kind referred to have the peculiarity, that unfavorable differences may occur in the temperature of the structural parts, which cause a displacement of the 20 objective systems and the ocular prism system relatively to each other in the direction of sight. Hence a relative displacement results, in the direction of the base line, of the images projected by the telescopes. This 25 displacement of the images affords, however, derangement of the instrument, since by means of a displacement of the same kind adjustment had previously been obtained. The telemeters referred to are therefore 30 according to the present invention equipped with an appliance which indicates any derangement due to the said displacement. This indicating appliance does not increase the diameter of the telemeter, as it 35 does not extend before the objective systems. It comprises, as essential parts, a physical mark in each telescope, an optical system reproducing each physical mark in an optical one, viz., in a real image, so that a pair 40 of control marks is formed either from one optical and one physical mark or from the two optical marks, and another optical system for magnifying the pair of control marks. The physical marks may serve as 45 the measuring marks of the telemeter, part of the reproducing system may be part of the telescopes proper and the magnifying system may serve as an ocular of the telemeter. Preferably the physical marks are 50 arranged in the objective casings and the

reproducing system is confined in the ocular prism casing. The indication of the appliance consists in a relative displacement of the pair of control marks.

In the annexed drawings: Figure 1 is a 60 diagrammatical front view of a stereoscopic telemeter constructed according to the invention. Fig. 2 is a diagrammatical plan view of the telemeter according to Fig. 1. Fig. 3 is a diagram of the field of view of 65 the magnifying system, appertaining to the telemeter according to Figs. 1 and 2. Fig. 4 is a diagram of the same field of view after displacement of the pair of control marks. Fig. 5 is a diagrammatical front 70 view of a second stereoscopic telemeter. Fig. 6 is a diagrammatical plan view of the telemeter according to Fig. 5. Fig. 7 is a diagram of the field of view of one of the 75 oculars of the telemeter according to Figs. 5 and 6, both of which oculars may act as magnifying systems, the pair of control marks being in adjustment. Fig. 8 is a diagram of the same field of view after displacement of the pair of control marks. 80 Fig. 9 is a diagrammatical front view of a coincidence telemeter constructed according to the invention. Fig. 10 is a diagrammatical plan view of the telemeter according to Fig. 9. Fig. 11 is a diagram of the 85 field of view of the magnifying system appertaining to the telemeter according to Figs. 9 and 10, the pair of control marks being in adjustment. Fig. 12 is a diagram of the same field of view after displacement of 90 the pair of control marks. Fig. 13 is a diagrammatic plan view of a second coincidence telemeter. Fig. 14 is a front view partly in section of a third stereoscopic telemeter. Fig. 15 is a horizontal section of the telemeter according to Fig. 14. Fig. 16 is a diagram of the field of view of the left ocular of the telemeter according to Figs. 14 and 15, which acts as the magnifying system, the pair of control marks being in adjustment. Fig. 17 is a diagram of the same field of view after displacement of the pair of 95 control marks.

The telemeter according to Figs. 1 to 4 is equipped with two oculars for stereoscopic measurement. The simple reflecting objective prisms *a* are placed in front of the objective lenses *b*. The ocular prism system consists of pentagonal optical square prisms *c*, which are provided with an image-erect- 105 110

ing ridge surface and are rigidly connected by a plate c^0 . Each ocular consists of a field lens d and an eye lens e , between which a rhomboidal prism f is arranged. By rotating the oculars about the axes of the field lenses adaptation to the interpupillary distance is obtained. The shiftable refracting prism g is the main part of the measuring appliance. The physical marks h and i belong to the indicating appliance, the mark h consisting of a long vertical stroke and the mark i of two shorter, but likewise vertical, strokes, the said marks being provided on the objectives. The lens k being the reproducing system projects a real image of the mark i on that place of the left objective lens, where the mark h is situated. This image and the mark h form the pair of control marks, the observation of which is facilitated by the prism l and the lenses m and n , these three parts forming together the magnifying system. So long as the ocular prism system $c^0 c^1$ and the objective systems $a^0 b^0$, $a^1 b^1$ have undergone no relative displacement in the direction of sight, the pair of control marks is seen in the position as represented in Fig. 3. If, however, for instance, the objective systems alone have moved toward the side of the observer, the pair of control marks appears in the position as represented in Fig. 4, because the lens k has taken no part in the movement and the image i^0 (projected by this lens) of the mark i (moved along with its objective lens b) has therefore performed a movement in the opposite direction to the mark h . If the telemeter be then re-adjusted, for instance, with the assistance of an object of known distance, it is only necessary to restore the original relative position of the pair of control marks as shown in Fig. 3, for which purpose the shiftable refracting prism g is arranged between the mark i and the lens k .

The objective systems of the telemeter according to Figs. 5 to 8 have pentagonal optical square prisms a^1 . The ocular prism system consists of two image-erecting ridge prisms c^1 . For the indicating appliance no special physical marks are provided, but the physical components p of the stereoscopic measuring mark, which according to Fig. 7 are arranged one in the middle of each telescope image field, on the hinder surfaces of the prisms c^1 , serve as such marks. Each mark p is reproduced in the plane of the other mark p by means of the parts c^1 and b of its own telescope, the two narrow prisms b and the parts b and c^1 of the other telescope. Each mark p and the image p^0 of the other (Fig. 7) form together a pair of control marks, because, as will be easily seen, with any relative displacement of the objective casings to the ocular prism casing the distance between them will be altered, Fig. 8. If the separating prism system of a

coincidence telemeter be substituted for the stereoscopic ocular prism system, one of the marks can be dispensed with. The pair of control marks is in that case composed from the individual physical mark in the one telescope field and the image of this mark in the other field. In the present case of two pairs of control marks each ocular may be used as the magnifying system of the indicating appliance. It is expedient to have the aperture of the telescope appertaining to the ocular chosen closed in observing the pair of control marks. Since the refracting prism g^1 of the measuring appliance participates in the reproduction of both marks p , the said observation is only possible after having set the measuring appliance upon the distance relatively to which the instrument has been adjusted, for instance, the distance infinity. If in this position of the measuring appliance the instrument after adjustment shows the pair of control marks lying one above the other as in Fig. 7, a relative position of this pair as in Fig. 8 would indicate derangement, which has arisen—if this position of the marks be observed in the right ocular—from a displacement of the objective casings toward the side of the observer. The prism g^1 would then have to be shifted—by setting the measuring appliance—until the pair of control marks has taken up its original relative position. To re-adjust the instrument deranged by the said setting, it would be only further necessary to place the index of the measuring scale again upon infinity.

In Figs. 9 to 12, the objective prisms a^2 are pentagonal optical square prisms and are each provided with an image-erecting ridge surface. The ocular prism system is a separating prism of well known form. It is composed of a simple reflecting prism q^1 and a prism q^2 having three reflecting surfaces, both prisms being cemented together. The lower half of the cemented surface is formed as the reflecting separating surface and is distinguished in Fig. 9 by shading. The separating prisms q^1 , q^2 , two reflecting prisms l^2 and l^3 and an objective r serve as the reproducing system and project real images h^0 and i^0 (Figs. 11 and 12) of the marks h and i in the field of view of the ocular $d e$. These two optical marks represent the pair of control marks, and the ocular $m n$ represents the magnifying system. Fig. 11 shows the pair of control marks in actual adjustment, Fig. 12 in derangement from the same cause supposed to have taken place in the former examples. The prism l^2 can be moved, as indicated in Fig. 10, together with the telemeter ocular $d e$ toward the left, by which the indicating appliance is rendered inoperative and the telemeter available for its proper purpose. The action and manipulation of the measuring appli-

ance represented by the prism g^1 are the same as in the former example.

In the example Fig. 13 the telemeter ocular d e has its place fixed behind the separating prism. The reproducing system consists of the separating prisms g^3 g^4 , the objective r and the reflecting prism l^4 . The control marks are formed in the field of the ocular m n , which is likewise fixed. Since the objectives b in this case lie in front of the objective prisms a^1 , it has been possible to arrange the marks h and i on these prisms. The ridge surfaces have been transferred from the objective prisms to the prisms g^3 and g^4 of the separating system, but it will be understood that this transfer has no influence upon the indicating appliance.

The stereoscopic telemeter according to Figs. 14 to 17 shows the pair of control marks h^o and i^o , as seen in Figs. 16 and 17, in a section of the image field of the left telescope. As in the first example this pair presents a constant indication, because its relative position is not influenced by the measuring device. The real images h^o and i^o of the marks h and i arranged on the objectives compose the pair of control marks. They are projected by a two-part separating prism s t of the simplest form, which is arranged on the carrier c^o of the ocular prisms c^2 and between these prisms. On the left ocular prism a double prism u^1 and on the right a simple prism u^2 is cemented, both for the purpose of producing the connection between the marks h and i and the separating prism s t , the double prism, however, with the further purpose of having a real image of the pair of control marks projected into the hinder surface of the left ocular prism c^2 equipped with the physical component of the measuring mark, in which hinder surface the left telescope image is located. This real image is produced by the objective r arranged with a reflecting prism l^5 behind the separating prism s t . The ocular of the left telescope is to be considered as the magnifying system of the indicating appliance. The pair of control marks is again expediently adjusted as shown in Fig. 16. A movement of the objective casings toward the side of the observer must then entail an alteration of the relative position of the pair as shown in Fig. 17. To restore the original relative position of the pair of control marks and at the same time to re-adjust the instrument, the refracting prism o^1 has only to be shifted, since this prism is concerned in the production of the reflected image o^o of the mark h in the same manner as in that of the left telescope image. The right telescope is equipped with the measuring appliance, which lies between the objective prism a^2 and the objective lens b . Its main part has the well known form of two equal refract-

ing prisms g^2 g^3 rotatable in opposite directions but through the same angle.

Regarding the mechanical arrangement according to Figs. 14 and 15, no explanation of the construction of the main casing is required, the external parts v of which represent the objective casings and the middle portion of which the ocular prism casing in the meaning of this specification. The rhomboidal prisms f are each combined with an eye lens e in one casing. These ocular casings are connected with the ocular prism casing v^o so as to be each rotatable about the axis of the field lens d . The movement of the refracting prisms g^2 and g^3 is effected by the axle of the measuring drum w and the bevel wheels x , x^1 , x^2 . The refracting prism o^1 can by rack and pinion operated by the knob y , Fig. 14, be shifted on the slide rest z .

I claim:

1. In a telemeter consisting of two telescopes the combination with two objective systems, an ocular prism system, an ocular system and a measuring appliance, of a middle casing containing the ocular prism system, two lateral casings containing the two objective systems and an appliance for indicating a displacement of the ocular prism casing and the objective casings relatively to each other in the direction of sight, this appliance comprising two physical marks, located one in each telescope, a reproducing system for obtaining two optical marks by projecting a real image of each physical mark, an optical mark and one of the remaining three marks being placed together in a convenient configuration so as to form a pair of control marks, and a magnifying system for this pair.

2. In a telemeter consisting of two telescopes the combination with two objective systems, an ocular prism system, an ocular system and a measuring appliance, of a middle casing containing the ocular prism system, two lateral casings containing the two objective systems, two physical marks located one in each objective casing, a reproducing system located in the ocular prism casing for obtaining two optical marks by projecting a real image of each physical mark, an optical mark and one of the remaining three marks being placed together in a convenient configuration so as to form a pair of control marks, and a magnifying system applied to this pair.

3. In a telemeter consisting of two telescopes the combination with two objective systems, an ocular prism system, an ocular system and a measuring appliance, of a middle casing containing the ocular prism system, two lateral casings containing the two objective systems, two physical marks located one in each objective casing, a reproducing system, located in the ocular

prism casing and including a separating prism system, for obtaining two optical marks by projecting a real image of each physical mark, these two optical marks being placed together in a convenient configuration so as to form a pair of control marks, and a magnifying system applied to this pair.

4. In a separating prism telemeter the combination with two objective systems, an ocular prism system, an ocular system and a measuring appliance, of a middle casing containing the separating prism system, two lateral casings containing the two objective

systems, two physical marks located one in each objective casing, a reproducing system, located in the separating prism casing and including the separating prism system of the telemeter, for obtaining two optical marks by projecting a real image of each physical mark, these two optical marks being placed together in a convenient configuration so as to form a pair of control marks, and a magnifying system applied to this pair.
